UNITED STATES PATENT OFFICE.

JOHN T. SHOEMAKER, OF FLINT, MICHIGAN, ASSIGNOR, BY DIRECT AND MESNE ASSIGNMENTS, TO FLINT AUTOMATIC HEATER COMPANY, A CORPORATION OF MICHIGAN.

CURLING-IRON HEATER.

Application filed October 29, 1926. Serial No. 145,027.

This invention relates to curling iron heaters, of the gas type, and has for its object to provide, a heater of such class including means, in a manner as hereinafter set forth, 5 for supporting the iron when being heated in a manner so it can be conveniently grasped and removed by the operator from the heater; with means in a manner as hereinafter set forth, for materially increasing 10 the flow of gas to the burner element of the heater and with such means actuated by the iron when the latter is mounted in position to be heated; and with means for materially reducing the flow of gas to the burner 15 element of the heater when the heated iron is removed and with the last mentioned means automatically operating to reduce the flow of gas to the burner element.

Further objects of the invention are to 20 provide a curling iron heater, in a manner as hereinafter set forth, and which is simple in its construction and arrangement, strong, durable, compact, thoroughly efficient in its use, automatic in its action to reduce the 25 flow of gas to the burner elements thereof, readily assembled, pleasing in appearance, and comparatively inexpensive to manufacture.

With the foregoing and other objects in 30 view, the invention consists of the novel construction, combination and arrangement of parts as hereinafter more specifically described, and illustrated in the accompanying drawings, wherein is shown an embodiment 35 of the invention, but it is to be understood that changes, variations and modifications can be resorted to which fall within the scope of the claims hereunto appended.

In the drawings wherein like reference 40 characters denote corresponding parts throughout the several views:—

Figure 1 is an end elevation of a curling iron heater in accordance with this invention.

Figure 2 is a section on line 2—2 Figure 45 1 and further illustrating a curling iron mounted on the heater and with the curling iron shown in dotted lines.

Figure 3 is a top plan view of the heater.

Referring to the drawings in detail 50 1 denotes a base, preferably of circular form and of the desired diameter and which is provided on its upper face, centrally thereof, with a vertically disposed collar 2, having 55 the inner face thereof threaded throughout

as at 3. The upper face of the base 1 centrally thereof is provided with a socket 4 and said collar 2 forms a continuation of the wall of the socket. The wall of the socket 4 is threaded throughout. 60

Detachably engaging with the base 1, is a tubular pedestal 5 having the periphery thereof, at its lower end, formed with threads 6 which engage with the threads 3 whereby the pedestal 5 is detachably connected to the base 1 and supported in upright position by the latter. The pedestal 5 has its inner face intermediate its ends formed with an integral annular flange 7 which is beveled as at 8 to provide a valve 70 seat. The pedestal 6 below the flange 4, and in proximity to its lower end is provided with an inlet opening 9 with which communicates a right angularly disposed, peripherally threaded nipple 10 which is employed 75 for connecting a gas supply line to the heater. The gas supply line is not shown.

Formed integral with the upper end of the pedestal 5, as well as communicating therewith, is a burner element of rectangular 80 contour and which is referred to generally by the reference character 11, and which includes a bottom 12, a pair of end walls 13, 14, a pair of side walls 15, 16 and a top wall 17 formed with a pair of spaced rows of 85 spaced ports 18. Each row of ports is positioned in the top wall 17 in proximity to the inner face of the side wall of the element 11. The bottom 12 between its transverse median and one end thereof is formed with 90 an opening 18', and the tubular pedestal 5 has its upper end formed integral with the outer face of the bottom 12, and the inner face of the pedestal 5 is flush with the wall of the opening 18. 95

Formed integral with the end wall 14 is a support 19, which is disposed transversely with respect to the element 11 and projects a substantial distance thereabove. The support 19 is of a length greater than the width 100 of the element 11 and is provided in its top edge with a groove 20 to receive one end of the curling iron 21. Formed integral with the end wall 13 and extending in a direction at right angles to said wall, is an arm 22, 105 of less width than the width of the element 11 and of a length to project a substantial distance beyond the base 1. The arm 22 is flat and has its outer end formed integral with a support 23, which is disposed trans- 110

versely with respect to the element 11 and extends a substantial distance thereabove. The support 23 is of greater length than the support 19 and is grooved as at 24 to receive 5 the handle end of the curling iron.

Cooperating with the flange 7, is a gas flow controlling valve 25 of tapered form and the size of the valve 25, relative to the seat 8, is such that when the heater is not 10 employed for heating the iron, the flow of gas to the burner element will be materially reduced. The reduction of the flow of gas is had when the valve 25 is in its lower-most position, as shown in Figure 2. The 15 valve 25 is shifted upwardly, to increase the flow of gas to the burner element 11, when the iron 21 is in position to be heated, or in other words, when the iron 21 is mounted on the supports 19, 23, as well as upon a shifting means for the valve 25. The reference character 26 denotes a vertically disposed valve stem of cylindrical cross section, and which has its lower end formed integral with the enlarged upper end of the valve 25. The stem 26 extends up through the pedestal 5, opening 18', through the gas receiving chamber 27 formed by the element 11, and further extends through an opening 28 formed in the top wall 17 30 of the element 11. The opening 28 is arranged centrally between the rows of jet openings 18. The stem projects a substantial distance above the top wall 17 of the element 11, and is formed with a bifurcated upper end 28. The top wall 17, of the element 11, between the opening 28 and support 19 is provided with a pair of vertically disposed apertured ears 29, between which is arranged a lever 30, the latter is pivotally 35 connected with the ears 29 by a pin 31. One end of the lever has a pin and slot connection 32, with the upper end of the stem 26, and the other end of the lever 30 is formed with an upstanding semi-circular tool engaging portion 32'. Interposed between that 40 end of the lever 30, which is provided with the portion 32', and the upper face of the wall 17 of the element 11, is a controlling spring 33 for the lever 30. The stem 26, lever 30 and spring 33 provides a spring controlled shifting means for the valve 25.

When the iron 21 is in the dotted line position shown in Figure 2, the weight thereof will rock the lever 30 on its pivot against the compression of the spring 33, whereby the stem 26 will be elevated and the valve 25 moved upwardly to increase the flow of gas to the burner element 11. When the iron 21 is removed from engagement with the portion 32' on the lever 30, spring 33 acts to rock the lever 30 in the opposite direction thereby lowering the stem 26, which will carry the valve 25 therewith, and materially reduce the flow of gas to the burner element.

It is thought the many advantages of a curling iron heater, in accordance with this invention can be readily understood, and although the preferred embodiment of the invention is as illustrated and described, yet it is to be understood that changes in the details of construction can be had which will fall within the scope of the invention as claimed.

What I claim is:—

1. In a gas heater for curling irons including a burner element formed with a gas receiving chamber having an opening in its top wall, a gas supply means opening into the chamber through the bottom wall thereof and provided with a valve seat, the combination of a valve stem extending through said opening and chamber and into said gas supply means and provided at its inner end with a valve coacting with said seat, a lever arranged over the top wall of said chamber, a pin and slot connection between the said lever and the outer end of said stem above said top wall, means for pivotally connecting said lever at a point between its transverse median and its outer end to said top wall, a tool engaging portion extending upwardly from the outer end of said lever and carried by the latter, and a controlling spring interposed between the outer end of said lever and said top wall. 95

2. In a curling iron heater of that type provided with a gas controlling element having a valve, the combination of a vertically extending tubular member provided on its inner face, intermediate its ends, with a valve seat coacting with the valve of said element and further provided below said seat with means for connecting with a gas supply, a base for the lower end of said member, a horizontally disposed, rectangular hollow casting including top, bottom, side and end walls and having its bottom connected to and opening intermediate its ends into the upper end of said member and its top provided with means for the passage therethrough of said element, said casting having its top formed at each side thereof with a row of spaced ports, a transversely disposed, vertically extending support at one end of the top of said casting and having its top edge grooved, an arm integral with and projecting from the other end of said top and disposed lengthwise with respect to said casting, a transversely extending vertically disposed support integral with the outer end of said arm, opposing and of greater length than the first mentioned support and grooved in its top edge, said supports being for maintaining a curling iron above said ports. 115

In testimony hereof, I affix my signature hereto. 120

JOHN T. SHOEMAKER. 125
